DESIGN FOR A WHEELED TOY

Erwin W. Muntz, Ottawa Lake, Mich., assignor
to Dudley W. Moor, Jr., and Eugene M. Belknap, both of Toledo, Ohio

Application January 8, 1945, Serial No. 117,336

Term of patent 14 years

(Cl. D34—15)

To all whom it may concern:

Be it known that I, Erwin Wm. Muntz, a citizen of the United States and resident of Ottawa Lake, in the county of Monroe and State of Michigan, have invented a new, original, and ornamental Design for a Wheeled Toy, of which the following is a specification, reference being had to the accompanying drawing, forming a part thereof.

In the drawing, Fig. 1 is a top plan view of a wheeled toy showing my design; Fig. 2 is a side view, and Fig. 3 an end view thereof.

I claim:

The ornamental design for a wheeled toy, substantially as shown.

ERWIN WM. MUNTZ.
